UNITED STATES PATENT OFFICE.

MARTIN RAJCHOK, OF HAMTRAMCK, MICHIGAN.

VALVE-NECK CONSTRUCTION FOR BOTTLES.

1,195,726.

Specification of Letters Patent. Patented Aug. 22, 1916.

Application filed March 21, 1916. Serial No. 85,602.

To all whom it may concern:

Be it known that I, MARTIN RAJCHOK, a subject of the Emperor of Austria-Hungary, residing at Hamtramck, in the county of Wayne and State of Michigan, have invented certain new and useful Improvements in Valve-Neck Construction for Bottles, of which the following is a specification.

10 This invention relates to new and useful improvements in valve neck construction for bottles.

15 The primary object of the invention is the provision of a bottle having a resiliently mounted normally closed outlet controlling valve carried thereby whereby the contents of the bottle may be tightly sealed while the bottle has the appearance of having a free open mouth, a locking means being arranged 20 thereon.

25 A further object of the device is the provision of a bottle neck formed separate from the bottle and securely attached thereto in permanent arrangement, the said neck being provided with a valve for the outlet mouth 30 of the bottle manually shiftable from a point in advance of the outlet of the mouth.

With these general objects in view and others that will appear as the nature of the 35 invention is better understood, the same consists in the novel combination and arrangement of parts hereinafter fully described, illustrated in the accompanying drawings and then claimed.

40 In the drawings forming a part of this application and in which like designating characters refer to corresponding parts throughout the several views:—Figure 1 is a side elevation of the bottle provided with the present device, the latter and the adjacent portion of the bottle being shown in central longitudinal section. Fig. 2 is an 45 end elevation of the device. Fig. 3 is a transverse sectional view taken upon line III—III of Fig. 1. Fig. 4 is a similar view taken upon line IV—IV of Fig. 1, viewed in the direction of the arrows. Fig. 5 is an 50 enlarged detail sectional view through the joint between the bottle and its neck and showing a portion of the valve seat for the mouth of the neck, and Fig. 6 is a detail 55 longitudinal sectional view through the free end of the bottle neck showing a modified form of operating stem provided with a locking device.

The present valve neck may be employed

on any form of bottle such as the bottle 10, the neck 11 being substantially cylindrical in form and having an annular groove 12 upon its inner end 13 adapted to seat over a 60 rib 14 having an enlarged free end 15 whereby the neck is permanently secured to the bottle by means of suitable cement 16 arranged in the receiving groove 12, as best 65 illustrated in Fig. 5 of the drawings.

An outlet opening 17 extends longitudinally through the neck 11 having a flared outlet or mouth 18 at the outer end 19 of the neck, while a packing ring 20 forming a valve seat is secured at the end of the outlet opening 17 in the end 13 of the neck.

70 A longitudinal bore 21 is arranged in the neck 11 at one side of the opening 17 and communicates with the interior of the bottle 10 by means of a perforation 22. A substantially disk-shaped flat valve 23 is arranged in the bottle 10 having an operating stem 24 of cylindrical form journaled in the perforation 22 and extending accurately out of the bottle neck through the bore 21 thereof. A turn knob or handle 25 is arranged outwardly of the bottle neck and has a cylindrical sleeve 26 fitting over the valve stem 24 and secured thereto by means of pins 27. The sleeve 26 extends into the bore 21 being 75 journaled therein while an expansion spring 28 is interposed between the inner end of the bore 21 and the adjacent end of the sleeve 26 whereby the valve 23 is maintained in flat 80 engagement with the inner end 13 of the neck 11. 85

It will thus be evident that when the valve 23 is normally positioned contacting the seat 20 that the valve will be retained closed by means of the spring 28, while the knob 25 90 may be operated for turning the valve stem 24 and thus shifting the valve 23 laterally, as best illustrated in Fig. 4 of the drawings, for either partially or entirely uncovering the seat 20 for allowing the contents of the bottle 10 to be poured out of the opening 17. Opposite recesses 29 are preferably arranged in the sides of the bottle 10 for accommodating the disk 23 at the opposite extremes of its shifted movement. A serviceable bottle is thus arranged with a valved neck permanently positioned thereon, the valve being normally maintained tightly closed but capable of being readily opened by slight pressure and turning of the sleeve 100 knob 25.

105 The valve stem 24' illustrated in Fig. 6

of the drawing is arranged within the bore 21' of the neck 11' and has a spring 28' for holding the valve normally closed after the manner of that illustrated in Fig. 1 with the exception however that the outer end of the spring 28' bears against a collar 20' secured in the bore 21' adjacent its open end, the stem 24' being freely slideable through the said collar. A sleeve 26' is freely screw-threaded upon the outer end of the stem 24' and has a finger plate 25' thereon. A transverse perforation 19' is arranged through the sleeve 26' and adapted to receive a removable cotter or pin 18' for preventing the sleeve 26' from turning upon the threaded portion of the stem 24'. The said stem 24' is provided with two transverse openings 17' adapted for the reception of the cotter pin 18', it being understood that when the sleeve is positioned with the cotter pin in the outer one of said openings as illustrated in Fig. 6, the stem 24' may be readily depressed for operating the valve while by removing the pin 18' and screwing the sleeve 26' down upon the outer face 16' of the bottle neck 11', the valve is maintained tightly closed and is locked in that position by inserting the pin 18' through the innermost opening 17' of the said stem 24'.

While the form of the invention herein shown and described is what is believed to

be the preferable embodiment thereof, it is nevertheless to be understood that minor changes may be made in the form, proportion and details of construction without departing from the spirit and scope of the invention as hereinafter claimed.

What I claim as new is:—

A device of the class described comprising a bottle having oppositely disposed valve receiving recesses adjacent its open end, a cylindrical neck fixedly secured to the open end thereof and having an eccentrically arranged longitudinally extending outlet opening therethrough having a flaring outlet end and further having an eccentrically arranged longitudinal bore at one side of said outlet opening communicating by means of a perforation with the interior of the bottle, a stem journaled through the said perforation, a disk valve eccentrically secured to the end of said stem within said bottle and projecting within one of the recesses when in its open position, a turn knob for said stem positioned outwardly of the neck, and resilient seating means for the said valve arranged within the said bore between the inner end thereof and the turn knob.

In testimony whereof I affix my signature.

MARTIN RAJCHOK.
